UNITED STATES PATENT OFFICE.

JOHN RALPH SURRELL, OF NEW YORK, N. Y.

BOILER-FURNACE.

No. 902,265.

Specification of Letters Patent.

Patented Oct. 27, 1908.

Application filed March 4, 1908. Serial No. 419,154.

To all whom it may concern:

Be it known that I, JOHN RALPH SURRELL, a subject of Great Britain, residing at the borough of Manhattan of the city of New York, in the county and State of New York, have invented a new and useful Boiler-Furnace, of which the following is a specification.

My invention relates to a boiler furnace provided with a fuel receptacle fed from above, having centrally located within it and surrounded by the fuel, a feed water heater, from which intensely heated water is conveyed to the water space and heat and flame are conveyed to the heat space of a steam boiler.

The objects of my invention are to provide a boiler furnace which can be readily attached to a steam boiler; by which heated water may be supplied to the steam boiler; by which a high pressure of dry steam may be maintained in the boiler; by which complete combustion of the fuel may be obtained with the extraction of a great degree of heat therefrom, without smoke and without combustible gases, except in slight measure when the furnace is first lighted; by which great saving of fuel is attained, and for which only a limited chimney draft is required, sufficient to carry off the smoke when first lighted and subsequently to carry off the non-combustible gases. I attain these objects by the device illustrated in the accompanying drawings in which.

Figure 1 is a central longitudinal section on the line 1—1 of Fig. 2. Fig. 2 is a horizontal section on the line 2—2 of Fig. 1. Fig. 3 is a vertical section on the line 3—3 of Fig. 2. Fig. 4 is a detail vertical section of a portion of the feed water heater on the line 4—4 of Fig. 5. Fig. 5 is a detail horizontal section of the feed water heater on the line 5—5 of Fig. 4. Fig. 6 is a detail vertical section of a modified form of my boiler furnace. Fig. 7 is a central longitudinal section of another modified form of my boiler furnace.

Similar numerals refer to similar parts throughout the several views.

My boiler furnace comprises a fuel receptacle, 10, Fig. 1, which may have water cooled sides or cooled by any suitable form of cooling. It is preferably cylindrical in form and arranged upon a suitable foundation in conjunction with a steam boiler. The fuel receptacle, 10, is open at the top, adapted

to be fed with fuel at that point, is provided with opening and closing covers for the top, 29, clinker doors 30, conveniently arranged in the sides, a grate 31, and an ash pit 32, having suitable doors for the removal of ashes.

Centrally placed within the fuel receptacle 10, and surrounded by the fuel is a feed water heater having a cylindrical base 11, resting upon the same foundation as the fuel receptacle but not communicating with the ash pit thereof. The base, 11, is open at its top and an annular collar, 12, is attached to the upper end of the base, 11, and connected with a water supply, 13. Water pipes, 14, are affixed at their lower ends to the annular collar, 12, and at their upper ends to a second or upper annular collar, 15, and so connected as to allow the passage of water from the lower annular collar, 12, to the upper annular collar 15. The water pipes 14 are arranged in the annular collars 12 and 15 to allow the passage of heat and flame between them from the fuel receptacle 10, the interior space resulting from their circular disposition in the annular collars forming the heat chamber 16, of the feed water heater. The upper annular collar 15 is connected with the water space of the steam boiler by pipes 17 and 18. A hood 19 which may be water cooled or otherwise suitably cooled, is carried from the upper annular collar 15 to the face of the steam boiler in such manner as to inclose the heat tubes of the steam boiler. A steam nozzle 20 connected with the steam boiler, or an outside steam supply, is inserted into the base 11 of the feed water heater, extending upward into the heat chamber 16 to a point slightly above the annular collar 12. The base 11 of the feed water heater is provided with a damper chamber 21 having a regulating door 22, the damper chamber having no communication with the ash pit of the fuel receptacle. A heat case 24, Figs. 1, 6 and 7, which may be water cooled or by any suitable form of cooling, is placed around the steam boiler, arranged, Figs. 1 and 6, so that the heat from the heat chamber of the feed water heater first passes through the boiler tubes and thence around and under the boiler to the chimney.

Fig. 7, shows a modified form designed to pass from the heat chamber of the feed water heater first under the boiler and thence around and through the tubes to the chimney. The heat case, 24, has at its rear end

a damper door, 25. An injector, 28, adapted to use steam or oil or these combined is inserted into the hood, 19, to drive and increase the heat and flame from the heat chamber of the feed water heater through the heat space of the steam boiler.

The modified forms of my boiler furnace, Figs. 6 and 7, are provided with a coil of water pipes, 26, instead of the two annular coils and the vertical water pipes, the coil, 26, Fig. 6, being carried up into the hood, 19, and the water from the feed water heater admitted to the steam boiler at a point above the tubes. In the form shown in Fig. 7, the hood, 19, is made lower and the coil, 26, carried up only to a point substantially in a line with the top of the fuel receptacle 10, and thence as a pipe, 27, enters the boiler at a point below the tubes.

20 The operation of my boiler furnace is as follows: The fuel receptacle, 10, having been filled with suitable kindling and fuel, to wit, coal, soft or hard, to a point about six inches or slightly below its top, the fire is started, 25 the top covers, 29, of the fuel receptacle being kept open and the regulating door, 22, of the damper chamber 21, arranged to give draft to the base, 11, of the feed water heater, the doors of the ash pit being kept 30 closed. If the steam jet, 20, is attached to an outside steam supply it may be turned on to accelerate the draft through the heat chamber, 16, and thus the draft of the fuel receptacle. The fire in the fuel receptacle, 35 through the effect of the draft through the heat chamber of the feed water heater will gradually extend upward, steady, intense and red glowing to a point slightly below the top of the fuel receptacle. The heat and 40 flame from the fuel receptacle passing between the water pipes, 16, or the coil pipes, 26, as the case may be, will heat the water in the pipes to be conducted with increasing intensity to the water space of the steam 45 boiler and the heat and flame also passing into the heat chamber, 16, of the feed water heater, will be conveyed thence to the heat space of the steam boiler. To deaden the fire in my boiler furnace the regulating door, 50 22, of the damper chamber, 21, is closed, the top covers, 29, of the fuel receptacle 10 are closed and the damper door 25, in the heat case, 24, is opened.

What I claim and desire to protect by Letters Patent is:

1. A feed water heater for steam boilers having a water chamber and heating surfaces, said heater comprising a fuel receptacle having grate bars and an ash pit, a set 60 of connected piping mounted within said receptacle with a fuel space surrounding it and forming a chamber for air and gases within it, means for supplying water to one end of said piping, means connecting the other end of said piping with the water space of the 65 boiler for delivering the heated water thereto, and means placing said chamber in communication with the heating surfaces of

space of the boiler for delivering the heated water thereto, and means placing said chamber in communication with the heating surfaces of said boiler, substantially as described and set forth.

2. A feed water heater for steam boilers having a water chamber and heating surfaces, said heater comprising a fuel receptacle having grate bars and an ash pit, a set 70 of connected piping mounted within said receptacle with a fuel space surrounding it and forming a chamber for air and gases within it, means for supplying water to one end of said piping, means connecting the other end of said piping with the water space of the 75 boiler for delivering the heated water thereto, and means placing said chamber in communication with the heating surfaces of said boiler, said piping being vertically disposed within said receptacle and extending from the grate bars to the upper end thereof, and said chamber being open at its upper end, substantially as described and set forth.

3. A feed water heater for steam boilers 80 having a water chamber and heating surfaces, said heater comprising a fuel receptacle having grate bars and an ash pit, a set of connected piping mounted within said receptacle with a fuel space surrounding it and forming a chamber for air and gases within it, 85 means for supplying water to one end of said piping, means connecting the other end of said piping with the water space of the boiler for delivering the heated water thereto, means placing said chamber in communication with the heating surfaces of said boiler and means for leading external air to said chamber and having means for controlling the passage of said external air through the 90 same, substantially as described and set forth.

4. A feed water heater for steam boilers having a water chamber and heating surfaces, said heater comprising a fuel receptacle having grate-bars and an ash pit, a set 95 of connected piping mounted within said receptacle with a fuel space surrounding it and forming a chamber for air and gases within it, means for supplying water to one end of said piping, means connecting the other end of said piping with the water space of the 100 boiler for delivering the heated water thereto, and means placing said chamber in communication with the heating surfaces of 105 said boiler, said piping being vertically disposed within said receptacle upon a cylindrical base extending downward through the ash pit of said receptacle and forming a continuation of said chamber, means for leading external air through said base to said chamber, and means controlling the same, substantially as described and set forth.

5. A feed water heater for steam boilers having a water chamber and heating sur- 110

faces, said heater comprising a fuel receptacle having top covers, clinker doors, grate-bars and an ash pit, a set of connected piping mounted within said receptacle with a fuel space surrounding it and forming a chamber for air and gases within it, means for supplying water to one end of said piping, means connecting the other end of said piping with the water space of the boiler for delivering the heated water thereto, and means placing said chamber in communication with the heat surfaces of said boiler, said piping being vertically disposed within said receptacle and having at its upper and lower ends an annular collar, the lower annular collar resting upon a cylindrical base extending downward through the ash pit, said base forming a continuation of said chamber and having means leading external air thereto, and means controlling the passage of said external air through the same, substantially as described and set forth.

6. In a feed water heater for steam boilers having a water chamber and heating surfaces, said heater having a fuel receptacle with grate-bars and an ash pit, means supplying water to said heater, means conveying the heated water from said heater to the water chamber of the boiler, means conveying air and gases from said heater to the heating surfaces of the boiler, and the cylindrical base having means leading external air therethrough, and means controlling the same, the set of connected piping vertically disposed in said fuel receptacle with a fuel space surrounding it and forming a chamber for air and gases within it, substantially as described and for the purpose set forth.

7. In a feed water heater for steam boilers

having a water chamber and heating surfaces, said heater having a fuel receptacle with grate-bars and an ash pit, means supplying water to said heater, means conveying the heated water from said heater to the water chamber of the boiler, means conveying air and gases from said heater to the heating surfaces of the boiler, and the cylindrical base having means leading external air therethrough and means controlling the same, the set of connected piping vertically disposed within said fuel receptacle with a fuel space surrounding it and forming a chamber for air and gases within it, and having at its upper and lower end an annular collar, substantially as described and for the purpose set forth.

8. In a feed water heater for steam boilers having a water chamber and heating surfaces, said heater having a fuel receptacle with an ash-pit and grate-bars, means supplying water to said heater, means conveying the heated water from said heater to the water chamber of the boiler, the set of connected piping vertically disposed in said fuel receptacle, and having a fuel space surrounding it and forming a chamber for air and gases within it, and the cylindrical base having means leading external air therethrough, and means controlling the same, the hood communicating between the air and gas chamber of said set of connected piping and the heating surface of the boiler, substantially as described and for the purpose set forth.
